UNITED STATES PATENT OFFICE.

WALTER WATTS, OF NEW YORK, N. Y.

FUSE PLUG.

Application filed February 16, 1922. Serial No. 537,045.

To all whom it may concern:

Be it known that I, WALTER WATTS, a subject of the King of Great Britain, and a resident of the city of New York, borough of Manhattan, in the county and State of New York, have invented a new and Improved Fuse Plug, of which the following is a full, clear, and exact description.

The present invention relates to an improvement in fuse plugs and seeks as its principal object to provide a fuse plug which includes a holder and a detachable fuse element whereby the latter may be renewed when fused in order to effect economy by saving of the holder.

At the present time it is the common practice to discard the holder when the fuse element has been fused. Furthermore in the present construction of fuse plugs considerable difficulty is experienced in detecting whether or not the fuse element has been fused, thus requiring considerable time in testing of the various plugs.

In the present invention the fuse element is constructed in such a manner as to dispose its weakest point in a position to be readily observed whereby when fused the necessity of testing is obviated.

As a further object the invention contemplates a fuse plug construction which renders the removal or association of the fuse element with its holder a simple operation and which precludes the necessity of removing the base of the plug from the socket of the instrument board or fuse box in replacing or removing said fuse element.

As a further object the invention aims to provide a positive means for effecting the engagement of the extremities of the fuse element with the contact elements of the plug whereby arcing due to a loose fit is reduced to a minimum.

With the above recited and other objects in view, the invention resides in the novel construction set forth in the following specification, particularly pointed out in the appended claims and illustrated in the accompanying drawings, it being understood that the right is reserved to embodiments other than those actually illustrated herein to the full extent indicated by the general meaning of the terms in which the claims are expressed.

In the drawing—

Figure 1 is a collective sectional view il-

lustrating the cap or head of the fuse plug removed from the base.

Fig. 2 is a side elevation of the base with the cap or head associated therewith and illustrating the latter in section, said section being taken approximately at a right angle to Fig. 1.

Fig. 3 is a plan view of the base.

Fig. 4 is a similar view of the cap or head.

Fig. 5 is a plan view of the fuse element prior to its association with the holder.

Referring to the drawings by characters of reference the fuse plug consists of a base 10 preferably constructed of insulating material such as porcelain which is provided with a threaded extension 11 having a metallic peripheral shell 12 which constitutes a shell contact for connecting the spring terminal 13 with a source of electrical energy when the plug is inserted in a socket. A central metallic stud 14 is arranged axially of the extension 11 and is electrically connected to the opposite spring terminal 15. The spring terminals 13 and 15 are arranged within the diametrically opposed sockets 16 of the plug base and said base is provided at its upper surface with a transverse rib 17 concaved as at 18 to provide the spaced upstanding supporting lugs 19 upon which the fuse element 20 is supported at its opposite ends. The

head or cap 21 of the fuse plug is provided on its under side with a transverse recess 22 with which a superposed recess 23 of a lesser length communicates to provide shoulders 24. The recess 23 further communicates with a sight opening 25 extending through the upper wall of the cap or head which is closed by means of a transparent panel 26 preferably of mica. The cap is provided with a pair of diametrically disposed depending contact legs 27 which are designed to be received within the sockets 16 of the base and which are adapted to be frictionally engaged by the spring contacts 13 and 15 to retain the cap against casual displacement or separation from the base. The contact legs 27 are each provided with an arcuate extension 28 the free extremities 29 of which are respectively disposed within the recess 22 at the opposite ends thereof. The legs 27 and extensions 28 are of a conducting material whereby when the plug is inserted in a socket the current will flow from the stud 14 to the spring contact 15, thence through

the contact leg 27 to one extremity of the

base and through the other extremity to the stud 14. The legs 27 and extensions 28 are of a conducting material whereby when the plug is inserted in a socket the current will flow from the stud 14 to the spring contact 15, thence through

the contact leg 27 to one extremity of the

extension 28, through the fuse element 20 to the opposite extremity 29 of the opposite extension 28, the leg 27, the spring contact 13, thence to the shell contact 12. The fuse element 20 consists of a strip of fusible material of rectangular formation which is provided in its opposite longitudinal edges with arcuate cutaway portions 30 to provide enlarged opposite extremities which are joined 10 by a central portion of gradually decreasing width and strength toward the central portion thereof. In use the fusible element 20 is supported at its opposite ends by the lugs 19 and the cap 21 is associated with the base 15 10 by inserting the legs 27 in the sockets 16, thereby impinging and clamping the opposite ends of the fusible element between the extremities 29 and the outer sides of the lugs 19 or the rib 17 to establish electrical 20 communication from the circuit wires through said fusible element. The arrangement and association of the fusible element with the holder disposes the weakest or narrowest portion of the same in direct alignment 25 with the sight opening 25 whereby the condition of said fusible element will be readily apparent to the observer. Under this arrangement the necessity of testing the various plugs to detect the fused plug is obviated as the fusible element is bound to fuse 30 at a point where it can be readily observed. Furthermore when the fuse element becomes fused it may be readily replaced at a small expense by removing the cap or head 21 and 35 inserting a new element and this without the necessity of removing the base from the fuse box socket. It should be further noted that the construction and arrangement insures at all times a close contact of the extremities of 40 the fuse element with the contact members, thus eliminating any possibility of arcing. The removal or insertion of the plug as a whole may be accomplished in the usual manner and the common practice of discard-

ing the holder or entire plug when the fusible element is destroyed is eliminated, thus effecting economy. 45

I claim:

1. In a fuse plug, a plug body having diametrically disposed sockets and spaced lugs 50 projecting from one end, insulated terminal contacts on the opposite end, spring contact fingers arranged within the sockets and connected to said terminal contacts, a detachable head having a recess for the reception 55 of the lugs, spaced contact legs adapted to enter the sockets and frictionally engage the spring finger contacts for retaining the head in associated relation with the plug body, said legs having extensions respectively arranged in the opposite ends of the recess, and a detachable fuse element positioned over the lugs with its opposite ends in clamping engagement between the leg extensions 60 at the end of the recess and the outer sides of the lugs to establish electrical communication 65 with the plug terminal contacts. 70

2. A fuse plug comprising a plug body of insulating material having a threaded extension, a threaded shell fitted over said extension, a central contact terminal extending therethrough, a pair of sockets in the opposite end of the plug body, spring contact fingers connected respectively to the shell and the central terminal, a pair of lugs 75 projecting from the socketed end of the plug body, a head having a recess in the end confronting the plug body for the reception of the lugs, contact legs projecting therefrom and insertable within the sockets for frictional engagement with the spring fingers, extensions from said legs arranged within the opposite ends of the recess, a fuse element positioned over said lugs and clamped at its opposite extremity between the extensions 80 of said legs and the outer side of the lugs. 85

WALTER WATTS.
